By A. A. Barker, Atty,

UNITED STATES PATENT OFFICE.

HARRY W. GODDARD, OF SPENCER, MASSACHUSETTS.

DESIGN FOR A NAIL OR SLUG.

SPECIFICATION forming part of Design No. 25,799, dated July 21, 1896.

Application filed April 17, 1896. Serial No. 584,182. Term of patent 3½ years.

To all whom it may concern:

Be it known that I, HARRY W. GODDARD, of Spencer, in the county of Worcester and State of Massachusetts, have invented a new and useful Design for a Nail or Slug; and I do hereby declare that the following is a full, clear, and exact description thereof, reference being had to the accompanying drawings, forming a part of this specification, and in which—

Figure 1 represents a perspective view of my newly-designed nail or slug. Fig. 2 is an end view thereof.

To enable others skilled in the art to which my said invention appertains to better understand the nature and purpose thereof, I will now proceed to describe it more in detail.

The object of my invention is to produce a new design for nails or slugs for use in ornamenting the heels of boots and shoes; and it consists of a nail or slug having two concave-shaped longitudinal grooves in each side thereof, forming two longitudinal necks between them, thin at the center and gradually increasing in thickness toward the middle and outer edges of said nail or slug to form a diamond-shaped central longitudinal rib, and also a longitudinal rib at each edge, as will be hereinafter more fully set forth.

In the drawings, *a* represents a nail or slug of the class named. *bb* are the concave grooves in the sides thereof, forming the narrow lon-

gitudinal necks *cc* at the center. *d* is the central longitudinal rib or thicker portion between said grooves, and *ee* the longitudinal ribs or thicker portion at the outer sides of the grooves. Said central longitudinal rib *d*, being formed by the union of the concave curves of the side grooves *bb*, is of diamond shape, and the two outer edges form similar half-diamond shapes in cross-section, which constitutes the essential feature of my invention.

I am aware that nails or slugs have been made with two longitudinal grooves upon each side, with a round or cylindrical shaped longitudinal rib at the center, and make no claim thereto. In view of this fact, however, I limit my invention to the specific shape or design of nail or slug shown and described, having the two concave-shaped grooves in the sides and a diamond-shaped central longitudinal rib.

What I claim, and desire to secure by Letters Patent, is—

The design for a nail-slug, substantially as set forth.

In witness whereof I have hereunto signed my name, in the presence of two witnesses, this 18th day of March, A. D. 1896.

HARRY W. GODDARD.
